PRODUCTION OF WOOD WOOL

Maximilian Lederer, Split, Yugoslavia, assignor to
Alexander Singer, Vienna, Austria

Application December 4, 1935, Serial No. 52,822
In Yugoslavia May 3, 1935

4 Claims. (Cl. 92—6)

My invention relates to the production of building material and more especially to products adapted for the building up of wall structures including blocks, boards, panels and slabs consisting of a mixture of wood wool and cement. It has particular reference to the production of wall products of the kind aforesaid which consists of a mixture of wood wool and Portland cement.

10 Wall products made of such a mixture of wood wool and cement have already been produced and to this end the wood wool has been subjected to an impregnation treatment before being mixed with the cement. This preliminary treatment 15 entails considerable expense.

I have now found that it is possible to combine and mix the wood wool with the cement in a very easy and efficient manner without previous impregnation by first treating the wood with steam 20 and thereafter mixing it with the cement.

If the steam treatment is applied to the wood wool, the boiler space required for this treatment is excessive, since the wood wool is very voluminous. I have however found that the problem 25 of pretreating the wood with steam can be solved in a very economical manner by combining it with the known removal of acetic acid, acetone, resin and the like with the aid of steam from the logs which serve as raw material in the production 30 of the wood wool.

By applying the treatment with steam to the logs or other wood material serving subsequently to produce wood wool I avoid the expenditure for the erection of special boiler plants and I greatly 35 reduce the cost of the treatment and the space required for it.

I have found that when treating the logs or other wood material including block wood and round wood with steam in accordance with this 40 invention, I can operate my process without any considerably increased pressure and need not use large boilers, since this process can be carried out in the available steel boilers or in subterranean chambers, which are supplied with steam 45 under slight pressure above normal, for instance with waste steam under a pressure of about .5 atmosphere above normal. I prefer acting in this manner with steam on block or round wood having a length of approximately .5 metre and 50 to assist the action of the steam by simultaneously spraying into the steam chamber neutral lead acetate which in mixing with the steam considerably increases and accelerates the impregnating action.

55 The logs or blocks of wood thus pretreated are then converted into wood wool in the usual manner.

In the drawing affixed to this specification and forming part thereof an apparatus adapted for 60 the carrying out of my invention is illustrated

diagrammatically by way of example in vertical section.

In the drawing, 1 is the brick or cement wall of the steam chamber and 2 is the sloping bottom of the chamber, from which liquid can flow through openings 3 into the exhaust conduit 4. 5 5 is a lattice bottom for supporting the material to be treated, 6 is a steam pipe extending through the top of the chamber and 7 is a pipe with a spray nozzle 8 for the introduction of neutral 10 acetate of lead. 9 are the logs, blocks or other wooden material to be treated, which rest on the lattice bottom 5.

The steam entering through the pipe 6 with a pressure of about 1.5 atmospheres mixes with 15 the solution of neutral acetate of lead supplied through pipe 7 and spray nozzle 8, the solution being finely distributed in the steam before coming in contact with the wood.

After the combined action of the steam and 20 the acetate of lead has been allowed to continue for a while, the wood thus treated is withdrawn from the steam chamber and is now converted 25 into wood wool in a well known manner. The wood wool thus produced has been found to be 25 excellently suited for the combination with cement and the building blocks or other wall material produced from such a mixture have been found to possess excellent properties.

Various changes may be made in the details 30 disclosed in the foregoing specification without departing from the invention or sacrificing the advantages thereof.

In the claims affixed to this specification no 35 selection of any particular modification of the invention is intended to the exclusion of other modifications thereof and the right to subsequently make claim in the present application to any modification not covered by these claims is expressly reserved.

40 I claim:—

1. In the production of wood wool adapted for use in the manufacture of wall products formed of a mixture of wood wool and cement the step of pretreating the wood, before it is converted 45 into wood wool, with steam under a pressure slightly above normal pressure.

2. In the production of wood wool adapted for use in the manufacture of wall products formed of a mixture of wood wool and cement the step of 50 acting on the wood with a mixture of steam under a pressure slightly above normal and with neutral acetate of lead.

3. The process of producing wood wool which 55 comprises acting on wood with a mixture of steam under slight pressure above normal and with acetate of lead and converting the wood thus treated into wood wool.

4. Wood wool containing acetate of lead.

MAXIMILIAN LEDERER. 60
